UNITED STATES PATENT OFFICE

CLINTON ALVORD, OF WORCESTER, MASSACHUSETTS, ASSIGNOR TO WORCESTER LOOM WORKS, OF WORCESTER, MASSACHUSETTS

TUFTED FABRIC WITH SIZED WEFT

Application filed May 31, 1930. Serial No. 458,052.

This invention relates to that class of fabrics known as tufted fabrics, and particularly to carpets and rugs. The main object of the invention is to overcome the serious shrinking in the width of the fabric during the process of weaving. Another object sought is the perfection of a better and more valuable floor covering by successfully employing a softer and smoother filling or weft 10 yarn in the body of the fabric. A third object is a new fabric which is manufactured preliminary to the finishing of the final form of fabric, and these and other objects as well as methods of manufacture are shown in the 15 drawings, described in the application and pointed out in the claims attached hereto.

Heretofore, in the manufacture of tufted fabrics, it has been necessary to use relatively stiff weft yarn, such as that made from jute, in order that the relative rigidity of the jute will oppose the softer warp strands and thus prevent the weft from crimping under the strain of the warp with the consequent lateral shrinkage of the fabric. This 25 shrinking in the width has been serious because each transverse row of pile tufts, in power looms, is inserted by mechanism extending clear across the width of the fabric. Unless the pitch of the fabric at the fell is 30 practically the same as the fixed pitch of the mechanism it is impossible to properly insert the pile tufts. Such a tuft insertion device is shown in Fig. 3 of patent to Wyman, 543,820 of July 30, 1895, while some of the 35 loom structure is illustrated in Figs. 1 and 2. In carpet weaving the pitch of the woven fabric is the number of tufts inserted in one inch of width, or the number of tufts woven into three quarters of a yard of width. The 40 usual pitch of an Axminster rug is seven to the inch or 189 to the three quarter yard. In hand looms the tufts were placed in position between the strands of warp by the fingers of the weaver and the natural shrinking of 45 the reticulated fabric was immaterial to the process of hand weaving. It was with the advent of power looms that the serious consequence of the shrinking of the fabric became evident, and as it is practically impossible to use temples on pile goods for hold-

ing out the goods, because of injury to the pile, and also because temples practically never hold the warp in uniform spacing the pioneers of this class of fabrics resorted to a relatively stiff jute weft which would resist the crimping effect of the cotton warp and thus prevent the shrinkage. But with the call for better tufted rugs, for rugs that were practically of the oriental type, it became necessary to employ a weft yarn that was 55 made of the same material as the warp and at once the fabric shrank during the process of weaving to such a degree as to shorten the pitch of the warp strands so markedly from the pitch of the mechanical tuft insertion 60 means that the tufts could not be properly placed between the strands of warp. Mechanical means as shown in my Patent No. 1,436,619 issued Nov. 21st, 1922, overcomes the difficulty, while this, my new invention, 65 enables me to use successfully a soft or cotton weft without the use of such mechanical means as shown in my patent above cited. The drawings of the loom illustrated in the 70 patent to Smith and Skinner, No. 186,374, January 16, 1877, show, in Figs. 5 and 5*, the usual weaving instrumentalities embodied in a loom for weaving tufted fabrics which include the usual shedding and the weft insertion mechanisms. Such a loom could not 75 weave tufted fabrics while using a cotton weft because the shrinkage would draw the warp strands out of register.

As a general thing cotton warp is used although warp yarns made of wool or any suitable material can be employed. But in the construction of high grade oriental like rugs it is necessary to employ warp and weft of substantially the same material and stiffness for the finished product, so that the feel of the 80 rug will be the same either warp or weft wise. I therefore starch or size my weft yarn until it becomes sufficiently stiff to resist any harmful crimping effect of the unsized warp and thus I prevent the disastrous shrinking of 85 the fabric.

The sized weft yarn weaves as easily as does the jute yarn. After various finishing operations have been made on the goods the fabric is washed to remove the starch, or size, from 90 95

the weft yarn and thereupon the weft becomes as soft as the warp and is crimped thereby so that the fabric shrinks in width. The size employed may be any substance appropriate for such a purpose which can be removed from the weft yarn by washing in water, or some adequate liquid, or the size can be removed by any other satisfactory method. The resulting fabric is of the soft back type and comparable to the well known Persian carpets.

Heretofore the stiff weft has been of jute and one of the well known troubles with jute is the fact that it cannot easily and cheaply be made into smooth yarn, or at least not comparable to the smoothness of a cotton yarn. When the tufts are of worsted stock, with fibres practically parallel, any of the frequently occurring nubs on the jute weft will separate two adjacent rows of tufts in a manner that is obviously objectionable and which destroys the handsome effect of a smooth and beautiful pile fabric. Almost any grade of a machine made cotton yarn is free from such nubs and therefore it is desirable to use smooth cotton yarn for weft when producing beautiful tufted fabrics, especially with tufts of worsted stock.

It is sometimes desirable to manufacture tufted rugs with the above described smooth cotton weft and not remove the size. This procedure enables the tufts to be composed of handsome worsted-like stock which will lie evenly in the fabric because of the non-existence of nubs which would exist were jute weft used. At the same time the rug remains as wide as it would if jute were used for weft instead of the sized cotton. This is a valuable feature and is accomplished by means of the sized cotton weft in a simple and inexpensive way.

In the drawings Fig. 1 shows a section of a three shot tufted fabric composed of three layers of warp strands with the weft shown in sections. Fig. 2 is a side view of the same with the warp shown in section. Fig. 3 is a sectional view identical to that shown in Fig. 2 after the size has been removed from the weft, while Fig. 4 shows a variation of the weft from that illustrated in Fig. 1.

In the drawings 1 is the warp which binds the two plies of weft strands together. 2 is the binder warp which interweaves with the weft strands in the upper ply while 3 is the stuffer warp separating the two plies. 4 represents the strands of weft in the top ply while 5 is the weft in the bottom ply. The tufts are marked 6 and are shown as passing through the two plies with the center of each tuft strand under weft 5 and showing on the bottom of the fabric while the two legs of the tuft strands appear as pile projecting from the body of the fabric on the face of the carpeting. The warps 1, 2, and 3 are generally of unsized cotton but they may be of

wool or any suitable fibre. The weft strands 4 and 5 are preferably of cotton which has been sized to stiffen it in order that the strain of the warps may not crimp the weft strands sufficiently to cause the fabric to shrink laterally to any appreciable extent and prevent the process of tuft insertion. The size employed to stiffen the weft may be any one of the substances commonly employed for such purpose and preferably soluble in water so that when the fabric is given a water wash the size is easily removed from the body of the fabric, whereupon the strain of the warp strands will cause the weft to crimp to a certain extent and the natural contraction, or shrinkage, of the fabric takes place. I do not limit myself to any specific sizing or substance for stiffening the weft or to any specific means for removing it after it has fulfilled its purpose of holding the fabric out to its original pitch while the tufts are being inserted. After the removal of the sizing the carpeting has a soft back as do the commercial oriental rugs. At times I may desire to give a luster to the tufts whereby the colors of the designs will shade because of the sheen of the yarn, and the sizing in the weft is preferably of a nature to be removed during the various manipulations to which the fabric is subjected.

In standard tufted fabrics there are seven hundred and fifty-six tufts across a nine foot or twelve quarter yard wide rug and if the weft is crimped two thousandths of an inch at each tuft then the rug will shrink one and a half inches laterally. It is evident that in a nine foot wide power loom and with the row of tufts being inserted by mechanical means, having a set pitch across the loom, that some method must be used to prevent a natural weaving shrinkage of one and one-half inches in order to successfully register the pitch of the warp strands with the mechanical pitch. Fig. 2 shows my size stiffened weft strands holding the warp out to the required register, while Fig. 3 shows in somewhat exaggerated form the crimping of the same weft strands, due to the strain of the warp, after the sizing has been removed and the fabric has shrunk.

Fig. 1 shows the weft as being a single strand as when delivered from a shuttle, while Fig. 4 illustrates each weft shot composed of two strands 7 and 8 as is the case in many tuft weaving looms in which the weft is inserted by means of a needle. Such a method is shown in Patent No. 446,177, issued Feb. 10th, 1891. I prefer the method of weft insertion shown in Fig. 4 for weaving the type of rug illustrated in this application.

What I claim as new and as my invention and what I desire to secure by Letters Patent is:—

1. The method of producing a tufted rug which comprises the interweaving of warp yarns substantially free from size with weft

composed of substantially the same material as the warp yarns but which has been stiffened by size, introducing tuft yarn into the fabric between said warp yarns by means of a mechanical tuft insertion device having an established and permanent lateral pitch and subsequently washing the size from the weft yarn.

2. The method of making a tufted carpeting which consists in interweaving relatively flexible warp yarns with a previously similarly flexible weft yarn but which has been rendered stiff by a dressing of size, inserting between said warp strands and under said weft strands suitable tufts by means of a mechanical tuft insertion device having an established and permanent pitch, and subsequently removing said size from said weft.

3. The method of making a tufted rug which consists in interweaving strands of flexible cotton warp with sized cotton weft on a power loom, inserting tufts between the strands of warp by means of a mechanical tuft insertion device having an established and permanent pitch, and subsequently removing the size from the weft by washing the fabric in a suitable solution.

4. The method of weaving a tufted carpet which consists in sizing weft, interweaving it with relatively unsized warp, inserting tuft yarns between the warp strands and under the weft by means of a mechanical tuft insertion device having an established and permanent pitch and subsequently removing the size from the weft.

5. A tufted fabric composed of relatively flexible warp interwoven with previously similarly flexible weft but which has been rendered stiff by a dressing of size whereby the weft strands will not bend and kink from the strain of the warp and allow the fabric to shrink materially in width, and with tuft yarns interwoven with the warp and weft.

6. A tufted fabric composed of a relatively flexible cotton warp interwoven with cotton weft which has been previously stiffened with a dressing of size whereby the weft strands will not bend and kink from the strain of the warp strands and allow the fabric to shrink materially in width, and with tuft yarns interwoven with the warp and weft.

In witness whereof I have subscribed the above specification May 27th, 1930.

CLINTON ALVORD.
